SEAL FOR ASH HOPPERS

Lauritz E. Mylting, Merchantville, N. J., assignor
to The Allen-Sherman-Hoff Company, Philadelphia, Pa., a corporation of Pennsylvania

Application April 28, 1950, Serial No. 158,816

5 Claims. (Cl. 110—165)

1

This invention relates generally to the furnace art and is particularly concerned with means for preventing escape of gases between the walls of an ash-receiving hopper and the walls of a fuel burning furnace surrounding an ash discharge opening from such a furnace.

Modern steam generating plants, for example those operated by public utilities, include furnaces having combustion chambers in which solid fuel is burned and having ash discharge openings in their lower portions through which the ash may be delivered, in the solid or liquid state, into a hopper positioned therebeneath. It is desirable that gases should neither flow into nor out of the combustion chamber through the ash discharge openings and, to prevent such flow, various expedients have been proposed to seal the space between the ash hopper walls and the furnace walls around the ash discharge openings. Such sealing is complicated by the fact that the furnace walls are heated to a much different temperature than the hopper walls and, hence, expand and contract to a different extent than do the hopper walls, and as a result of this unequal expansion and contraction, the hopper walls may not be rigidly attached to the furnace walls around the ash discharge openings.

One solution of the problem was described in U. S. Patent No. 2,275,652, granted on March 10, 1942, to Harold R. Pursel. The invention there disclosed has gone into extensive commercial use and has proven to be quite satisfactory, but it has the disadvantages that the walls depending transversely and longitudinally from the furnace were not readily protectable, by a refractory facing, against the intense heat from the combustion chamber, and flexible members were required to connect the ends of those depending walls at their ends to permit their relative movements with changing temperatures. Furthermore, it is difficult, if not impossible, to cool refractory material on the inner side of these depending walls. As a result of the first named disadvantage, refractory walls of various types were used to protect these depending metal walls. Another disadvantage was that the liquid in the trough was directly exposed to the intense heat of the furnace and, being open to the furnace, cooled solids at a rapid rate which necessitated frequent cleaning out of the trough.

The present invention solves the problem in a different manner and, by using a different combination and arrangement of parts, provides a seal of simplified construction which may be provided with a light refractory lining which is

2

water-cooled by the water in the trough and in which the water in the trough is not exposed to the direct heat of the furnace and is so far removed from the ash discharge opening that the quantity of solids which can enter the trough is quite limited.

While the present invention is of perhaps greatest value in conjunction with a powdered fuel burning furnace and its hopper, with which 10 parts it has been illustrated herein, the invention is also quite valuable with furnaces equipped with stokers of any of the various conventional kinds where the ash is in solid form as contrasted with a liquid form when it enters the 15 hopper.

The present invention will be better understood by those skilled in the art by reference to the accompanying drawings which form a part of this specification and the following description thereof.

In the drawings:

Fig. 1 is a fragmentary, vertical, transverse, sectional view through a powdered fuel burning furnace and its hopper and showing one form of 25 seal embodying the present invention; and

Fig. 2 is a fragmentary, sectional view showing a modified form of the present invention.

In Fig. 1, 1 designates the lower part of a powdered fuel burning furnace having a combustion chamber 2 and an ash discharge opening 3. 30 Opposite upstanding walls 4 of an open topped hopper are positioned to receive ashes discharged from chamber 2 through opening 3.

The seal between the furnace 1 and chamber 2 comprises a metal wall 10 depending from the furnace wall around discharge opening 3 and projecting into the hopper within walls 4 thereof. This endless depending metal wall 10 is provided with a refractory lining 11 on its inner side. At the lower end of wall 10 an endless horizontal wall 12 extends from within wall 10 to a point some distance outside thereof and then extends upwardly as at 13. Walls 10, 12 and 13 define an open topped endless trough which 45 extends all the way around the outer side of wall 11 and the ash discharge opening 3. The projection 14 of horizontal wall 12 inwardly beyond the vertical projection of depending wall 10 affords a support for the refractory material 11.

It will be seen that by maintaining a quantity of water in the trough 13 the depending wall 10 and its refractory lining 11 will be water-cooled and, hence, protected against the intense heat from the combustion chamber.

55 A metal wall 15 is secured to the hopper walls

4, extends inwardly therefrom and then vertically down into the trough, as at 16, between inner and outer walls 10 and 13 thereof. This wall 15 extends continuously around the discharge opening 13 and, together with the parts which are attached to the furnace and have just been described, acts as an effective seal against flow of gases either into or out of the combustion chamber through the upper end of the hopper.

Since the hopper walls never attain a temperature as high as that attained by the walls of the combustion chamber about the ash discharge opening, the hopper does not expand and contract to such an extent as do the furnace walls. Hence, with a trough having substantial width between walls 10 and 13, these trough-forming walls may expand and contract with the furnace walls without ever coming into contact with the depending portion 16 of wall 15.

In Fig. 2, the embodiment of the invention shown is somewhat different from that shown in Fig. 1. In Fig. 2, the furnace 1 has a similar combustion chamber and discharge opening 3, a depending endless metal wall 20, quite similar to wall 10 of Fig. 1, a refractory lining 21 on the inner side of wall 20 similar to lining 11 of Fig. 1, a horizontal wall 22 similar to wall 12 of Fig. 1, and an upwardly extending wall 23 similar to wall 13 of Fig. 1. Wall 22, unlike wall 12, has an upwardly extending inner edge 24 to act as a better support and retainer for the refractory lining 21. The hopper wall consists of an outside metal wall 30 and a refractory liner 31 therefor. Wall 30 extends horizontally, as at 32, on top of the liner 31 and affords support for a channel-shaped upright wall 33 which extends upwardly in telescoping relation with wall 23. The latter wall has a depending ledge 34 which telescopes with an upstanding flange 35 of wall 33 to afford a restricted passage from the interior of the hopper to the space between walls 23 and 33, this restricted passage acting to retard the movement of fine solids into the liquid in the trough between walls 20 and 23. At the upper end of wall 23, a metal wall 36 is secured and extends inwardly and then downwardly, as at 37, to project into the trough between walls 20 and 23 and to dip into water therein. The apparatus of Fig. 2 is substantially the same as that described above in connection with Fig. 1.

From the foregoing description, it will be understood that the apparatus of the present invention has a number of advantages. It makes it possible to provide a refractory lining for the depending wall 10 or 20 and thereby permits the use of relatively inexpensive materials for those walls which would not be resistant to the prevailing conditions in the absence of the refractory lining. The presence of the water against the outer side of these depending walls serves not only to cool these walls and their refractory linings, but also thereby to make it possible to use thinner linings. Furthermore, since the water seal is on the outside of the depending walls, the sealing walls 15 can be readily attached to the hopper walls and readily removed when necessary.

Since the trough is outside of the depending wall and the top surface of the water therein is removed some distance from the discharge opening 3, the quantity of fine solids which find their way into the hopper is considerably reduced.

Another and quite important advantage is that for a given header spacing the sealing elements can be kept a maximum distance from the dis-

charge opening of the combustion chamber, the hopper can be made considerably wider than otherwise and the depending walls 10 may be extended far enough down into the hopper to afford space for access and inspection doors in walls 15 and 36 above the troughs.

If the depending walls 10 or 20 are extended down far enough into the hopper, they can maintain in their shadow the troublesome water line in submerged hoppers. It will be understood that in these so-called submerged hoppers water is retained in the hopper to quench the ash and that it is somewhat difficult to maintain the lining in good condition at the surface level of the water due to the intense heating of the lining above the line and its much lower temperature below the surface of the water. By extending the present seal down far enough into the hopper to cast a shadow on the water line, the troubles with that portion of the hopper may be greatly minimized.

Having thus described the present invention so that others skilled in the art may be able to understand and practice the same, I state that what I desire to secure by Letters Patent is defined in what is claimed.

What is claimed is:

1. In apparatus of the class described including a fuel burning furnace having an ash discharge opening and a hopper positioned to receive ashes from said opening, the combination of a wall extending down from said furnace around said opening, a wall extending outward from the lower portion of said depending wall and then extending upwardly to form therewith an endless open-top trough for liquid, and a wall extending inwardly from the hopper walls and downwardly into said trough to seal the space between the trough and hopper wall against the escape of gas therebetween.

2. In apparatus of the class described including a fuel burning furnace having an ash discharge opening and a hopper positioned to receive ashes from said opening, the combination of a wall extending down from said furnace around said opening, a refractory lining on the inner side of said wall, a wall extending outward from the lower portion of said depending wall and then extending upwardly to form therewith an endless open-top trough for liquid, and a wall extending inwardly from the hopper walls and downwardly into said trough to seal the space between the trough and hopper wall against the escape of gas therebetween.

3. In apparatus of the class described including a fuel burning furnace having an ash discharge opening and a hopper positioned to receive ashes from said opening, the combination of a metal wall extending down from said furnace around said opening and into said hopper, a refractory lining on the inner side of said metal wall, a wall extending approximately horizontally outward from the lower portion of said depending wall and then extending upwardly approximately parallel thereto to form therewith an endless open-top trough for liquid, and a wall extending inwardly from the hopper walls and downwardly into said trough to seal the space between the trough and hopper wall against the escape of gas therebetween.

4. In apparatus of the class described including a fuel burning furnace having an ash discharge opening and a hopper positioned to receive ashes from said opening, the combination of a metal wall extending down from said furnace around

said opening and into said hopper, a refractory lining on the inner side of said metal wall, a wall extending approximately horizontally outward from the lower portion of said depending wall and then extending upwardly approximately parallel thereto to form therewith an endless open-top trough for liquid, said horizontal wall extending inwardly beyond the depending wall and affording support for said lining, and a wall extending inwardly from the hopper wall and downwardly into said trough to seal the space between the trough and hopper wall against the escape of gas therebetween.

5. In apparatus of the class described including a fuel burning furnace having an ash discharge opening and a hopper positioned to receive ashes from said opening, the combination of an endless metal wall extending down from said furnace around said opening toward the interior of said hopper, a refractory lining on the inner side of 10 said metal wall, an endless wall extending ap-

15

proximately horizontally outward from the lower portion of said depending wall and then extending upwardly to form therewith an endless open-top trough for liquid, and an endless wall extending inwardly from the hopper walls and downwardly into liquid in said trough to seal the space between the trough and hopper wall against the escape of gas therebetween.
